UNITED STATES PATENT OFFICE.

GILBERT G. SATRUM AND INGVALD B. SNARTEMO, OF OSLO SETTLEMENT, TEXAS.

BLACKBOARD-CLEANER.

1,255,053.

Specification of Letters Patent. Patented Jan. 29, 1918.

Application filed May 15, 1917. Serial No. 168,800.

To all whom it may concern:

Be it known that we, GILBERT G. SATRUM and INGVALD B. SNARTEMO, citizens of the United States, residing at Oslo Settlement, 5 in the county of Hansford and State of Texas, have invented new and useful Improvements in Blackboard-Cleaners, of which the following is a specification.

Our invention relates to blackboard cleaners and has for its objects; first, to provide a blackboard cleaner of a simple and durable construction, second to provide a blackboard cleaner in which is incorporated a water reservoir having manually controlled 15 means for communicating the water of the reservoir to the rubbing element of the cleaner, thirdly, to provide a blackboard cleaner in which is incorporated a rubbing element and a fluid chamber communicating therewith, the rubbing element being 20 easily and quickly removable from the main body portion of the device to replace or clean the same.

With these and other objects in view 25 which will be hereinafter fully described and particularly pointed out in the claim, the invention consists in the novel construction and arrangement of parts illustrated in the accompanying drawings forming a 30 part of this specification, in which:—

Figure 1 is a view in oblique perspective of a blackboard cleaner embodying our invention.

Fig. 2 is a central sectional elevation of 35 the same.

Fig. 3 is a top plan view of the sponge retaining cage of the device.

Fig. 4 is a bottom plan view of the body 40 of the device with the sponge retaining cage removed therefrom.

Like characters of reference indicate like parts in the various views.

In the drawings 1 designates generally the body of the device. The body has a 45 fluid reservoir 2 formed therein having the longitudinal sides thereof shaped to fit the handle, as designated at 3, in Fig. 1. The bottom wall of the fluid reservoir, which is designated at 4, is flat and a flange 5 projects downwardly therefrom and forms an 50 inclosure below said bottom wall. Two ports 6 are formed in the bottom wall of the fluid reservoir. A stud 7 is secured upon the under side of the wall at a point intermediate the two ports 6. A valve 8 is pivotally mounted upon the stud 7 and has 55 surfaces 9 engaging the under surface of the bottom wall adjacent the ports 6. A hole 10 is formed in the valve 8 at each end thereof and is adapted to register with respective ports 6 when the valve 8 is in its middle position. When the valve is moved to either of its side positions the holes 10 are moved out of registry with the ports 6 and the surfaces 9 close the ports. A slot 60 11 is formed in the flange 5 and an actuating handle 12 of the valve 8 projects therefrom and has a manipulating knob 13 mounted thereon exteriorly of the inclosure. The portion of the valve 8 which lies between the surfaces 9, as designated at 4, which is engaged by the stud 7 is resilient and co-operates with said stud to hold the surfaces 9 in tight engagement with the under surface of the bottom wall 4. A cap 70 15 is screw threaded into a filler hole 16 formed in one of the end walls of the reservoir adjacent the top thereof.

A sponge retaining cage 17 is provided and comprises vertical sides 18 forming an 80 inclosure and adapted to fit within the inclosure of the flange 5. A pair of downwardly shouldered projections 19 are formed upon opposite sides of the cage 17 and are adapted to engage corresponding upwardly 85 projecting shoulders 20 formed on the flange 5 whereby the sponge retaining cage may be properly secured within the inclosure of the flange 5. A series of cross rods 21 are movably secured to the sides of the 90 sponge retaining cage and extend across the inclosure of the same and are adapted to pass through a sponge 22 or other suitable rubbing material to hold the same within the cage. The sponge is preferably rectangular in shape and having a greater height than the sides 18 so that a portion thereof may project below the bottom edges of said side. The top of the sponge is flush with the top edge of the sides 18, said edge being 100 considerably lower than the bottom 4. The engagement of the shoulders 19 and 20 secures the cage within the flange 5 with the bottom edge of said cage flush with the bottom edge of the flange whereby sufficient 105 space is provided above the cage and sponge for the valve 8. When it is desired to remove the cage from the flange the sides upon which the shoulders 19 are formed are moved toward each other to disengage the 110 same from the shoulders. The cage is then lifted out from engagement with the flange.

When it is desired to replace the sponge the cross rods 21 are removed and the sponge pulled out from within the inclosure of the casing. The cross rods 21 are secured upon the sides 18 by bending over the ends thereof which extend beyond the sides, the holes in the casing through which they pass being countersunk from the outer surface of the sides, as designated at 23, to accommodate 10 the bent over ends of the cross rods.

Having thus fully described our invention, we claim:

15 A blackboard cleaner comprising a water receptacle of elongated form having its longitudinal sides made to conform to the

hand and having perforations in its bottom, a flange projecting below said bottom and forming a rectangular casing, a valve on the bottom for controlling said perforations, shoulders on said flange, a sponge cage of 20 less height than the flange and adapted to fit within the casing, spring projections on said cage for engaging with said shoulders to hold the cage within the casing and means for removably holding the sponge in said 25 cage.

In testimony whereof we affix our signatures:

GILBERT G. SATRUM.
INGVALD B. SNARTEMO.
